(57) CLAIM

The ornamental design for a portable dog bowl, as shown and described.

DESCRIPTION

FIG. 1 is a front, top and left perspective view of a portable dog bowl showing the new design;

FIG. 2 is a front elevation view of the portable dog bowl of FIG. 1;

FIG. 3 is a left side elevation view of the portable dog bowl of FIG. 1;

FIG. 4 is a right side elevation view of the portable dog bowl of FIG. 1;

FIG. 5 is a back elevation view of the portable dog bowl of FIG. 1;

FIG. 6 is a top plan view of the portable dog bowl of FIG. 1; and,

FIG. 7 is a bottom plan view of the portable dog bowl of FIG. 1.

The broken lines illustrate portions of the portable dog bowl that form no part of the claimed design.
